UNITED STATES PATENT OFFICE.

FRANK T. MURATA, OF CANON CITY, COLORADO.

TOBACCO-PIPE.

1,089,254.

Specification of Letters Patent. Patented Mar. 3, 1914.

Application filed November 26, 1912. Serial No. 733,652.

To all whom it may concern:

Be it known that I, FRANK T. MURATA, a citizen of the United States, residing at Canon City, in the county of Fremont and State of Colorado, have invented new and useful Improvements in Tobacco-Pipes, of which the following is a specification.

This invention relates to improvements in tobacco pipes, particularly with reference to the provision of a tobacco pipe with a removable stem and with a detachable holder and sleeve to enable a cartridge of absorbent material to be used in the stem of the pipe to absorb the nicotine and deleterious juices and prevent them from reaching the mouth of the smoker and to also enable the various parts to be readily disassembled and the pipe to be cleaned, the invention consisting in the construction, combination and arrangement of devices hereinafter described and claimed.

In the accompanying drawing:—Figure 1 is a longitudinal central sectional view of a tobacco pipe constructed in accordance with my invention. Fig. 2 is a transverse sectional view on the plane indicated by the line *a—a* of Fig. 1. Fig. 3 is a similar view on the plane indicated by the line *b—b* of Fig. 1. Fig. 4 is an enlarged vertical longitudinal sectional view of the meeting ends of the pipe stem and mouth piece and of the cartridge holder which connects them, the sleeve and the cartridge being also shown.

The bowl 1 of my improved tobacco pipe may be of any suitable size and shape and made of any suitable material and is here shown as provided with an integral stem 2. The stem is provided in its outer end 35 with a chamber 3 the wall of which is threaded for a suitable distance to receive the threaded end 4 of a tubular detachable cartridge holder 5. The cartridge holder may be made of horn, rubber or any other 40 suitable material. The outer end of the cartridge holder projects from that of the stem of the pipe and the inner end of the mouth piece 6 is fitted on and screwed to the cartridge holder so that the cartridge 45 holder also forms a coupling member to

detachably connect the mouth piece to the stem of the pipe. The mouth piece has a chamber 7 in its inner end to receive the outer portion of the cartridge holder. The mouth piece may be made of any suitable 55 material and may be of any suitable size and shape or design.

Longitudinally movable in the outer portion of the cartridge holder is a tubular sleeve 8, the diameter of which is less than 60 the bore of the cartridge holder, the said sleeve being provided at its ends with flanges 9 which form diametrical enlargements thereof. Stop screws 10 are threaded in openings in opposite sides of the sleeve 65 and coact with the flanges 9 of the latter to limit the longitudinal movement of the sleeve and prevent the same from becoming casually detached from the cartridge holder.

In connection with my improved pipe, I 70 employ an absorbent cartridge 11 which is preferably a tube of suitable length and diameter to fit in the chamber formed in the cartridge holder between the sleeve 8 and the stem of the pipe, the said tube being 75 preferably made of paper, straw or the like and being filled with absorbent material, such, for instance, as absorbent cotton and indicated at 12. These cartridges may be readily produced at small cost and preferably one is used for each smoke. The nicotine and deleterious juices are absorbed and retained by the cartridge and prevented 80 from passing to the mouth of the smoker.

The parts of the pipe may be readily disassembled to enable a used cartridge to be discarded and another substituted in its place and to enable the parts to be readily and thoroughly cleansed.

While I have herein shown and described 85 a preferred form of my invention, I would have it understood that changes may be made in the form, proportion and construction of the several parts without departing from the spirit of the invention and within 90 the scope of the appended claim.

I claim:

A tobacco pipe, cigar holder, or the like having a stem provided with a chamber in its outer end and communicating with its 100

bore, a mouth piece having a chamber in its inner end, a tubular cartridge holder having threaded engagement with the chambers of the stem and mouth piece and forming a coupling member between them, a sleeve mounted for longitudinal movement in the cartridge holder and connected thereto and removable therewith from the stem and

mouth piece, said sleeve having a contracted bore extending from end to end thereof. 10

In testimony whereof I affix my signature in presence of two witnesses.

FRANK T. MURATA.
